CLAIM

The ornamental design for a snack holder, as shown and described.

DESCRIPTION

FIG. 1 is a front view of a snack holder of our new design;

FIG. 2 is a right side view of FIG. 1;

FIG. 3 is a left side view of FIG. 1;

FIG. 4 is a rear view of FIG. 1;

FIG. 5 is a top view of FIG. 1;

FIG. 6 is a bottom view of FIG. 1; and,

FIG. 7 is a top, right side, and front perspective view of FIG. 1.

The broken lines disclosure in the views represents portions of the snack holder which form no part of the claimed design.
